(57) **CLAIM**

The ornamental design for a tampering detection clamping box for ingress and egress lines, as shown and described.

DESCRIPTION

FIG. 1 is a perspective view of the tampering detection clamping box for ingress and egress lines, the tampering detection clamping box for ingress/egress lines being presented in a fully open state;

FIG. 2 is another perspective view thereof;

FIG. 3 is a top view thereof;

FIG. 4 is a leftside view thereof;

FIG. 5 is a rightside view thereof;

FIG. 6 is a front view thereof;

FIG. 7 is a rear view thereof;

FIG. 8 is a bottom view thereof;

FIG. 9 is another perspective view thereof, the tampering detection clamping box for ingress and egress lines being presented in an alternate partially open state; and,

FIG. 10 is another perspective thereof, the tampering detection clamping box for ingress and egress lines being presented in an alternate fully closed state.

The broken lines in the drawings illustrate portions of the tampering detection clamping box for ingress/egress lines that form no part of the claimed design. The oblique, lighter lines residing on a front wall of the tampering detection clamping box for ingress/egress lines as best shown in FIGS. 6, 9, and 10, represent a transparent surface and wall.

1 Claim, 4 Drawing Sheets
